UNITED STATES PATENT OFFICE.

WILLIAM S. MAGEE, OF FENELTON, AND CHARLES R. McCARREN, OF WEST WINFIELD,
PENNSYLVANIA.

RAIL-FASTENING MEANS.

1,124,773.

Specification of Letters Patent. Patented Jan. 12, 1915.

Application filed October 7, 1914. Serial No. 865,556.

To all whom it may concern:

Be it known that we, WILLIAM S. MAGEE and CHARLES R. McCARREN, citizens of the United States, residing at Fenelton and West Winfield, respectively, in the county of Butler and State of Pennsylvania, have invented certain new and useful Improvements in Rail-Fastening Means, of which the following is a specification, reference 10 being had to the accompanying drawings.

This invention relates to new and useful improvements in rail fastening means and more particularly to the fastening means disclosed in my pending application on rail- 15 way ties and fasteners, which was filed July 29th, 1914, Serial Number 853,902; the main object of the present invention being the provision of an improved fastening means adapted to be used in connection with my 20 improved tie described and illustrated in the above noted application, wherein the rails which are mounted upon the ties will be securely held against any lateral or longitudinal movement.

Another object of the present invention is the provision of a rail fastener of the above character which will possess advantages in points of efficiency and durability, is inexpensive to manufacture and, at the 30 same time, is simple in construction and operation.

With the above and other objects in view, the invention consists in the novel features of construction, combination and arrangement of parts as will be hereinafter referred to and more particularly pointed out in the specification and claim.

In the accompanying drawing forming a part of this application, Figure 1 is a side 40 elevation of a railway tie, illustrating in connection therewith our improved fastener, parts of the tie and fastener being illustrated in cross section. Fig. 2 is a detail elevation, parts of the tie and fastener being 45 illustrated in section. Fig. 3 is a top plan view of the chair plate; and Fig. 4 is a detail perspective view illustrating a slightly modified form of the fastener, the fastening bolts being illustrated in cross section.

In carrying out our invention, 1 indicates in general the base of the tie, which is preferably of the same form as illustrated in our prior application and which is formed of metal and includes the base portion 2 and the upright portion 3, upon which the

body 4 of the tie is mounted. The body of the tie is provided upon its upper face at each end thereof, with the serrated teeth 5, the purpose of which will be hereinafter more fully set forth. Mounted upon the tie 50 at each end thereof, are the rail chairs 6 which form suitable seats for the rails 7 and include the base member 8 having longitudinal flanges 9 formed upon the upper face thereof between which the base flanges of the 55 rails are adapted to be disposed. The ends of the chairs 6 are provided with downwardly extending transverse flanges 10 which are adapted to engage upon opposite sides of the body of the tie to prevent longitudinal movement of the chairs after being placed in position.

It will be noted that the lower faces of the rail chairs 6 are provided with serrations 11 which are adapted for engagement 75 with the serrations 5 formed upon the body of the tie to prevent lateral movement of the rail chairs after being placed in position. In order to retain the rails in position and securely hold them against any lateral or 80 tilting movement, the rail fasteners 12 are provided which include a substantially horizontal body portion 13 having upon its inner edge the upwardly projecting flange 14 which is adapted for engagement with the 85 web portion of the rail and also to engage beneath the tread portion, as clearly illustrated in Fig. 1. Formed integral with the body portion 13, is a downwardly projecting flange 15, the lower edge of which is serrated, as shown at 16, whereby it will engage 90 with the serrations 5 upon the upper face of the body of the tie to securely hold the fasteners against lateral movement.

The rail fasteners 12 are further secured 95 in position by means of bolts 17 which are extended up through the body of the tie, through suitable recesses 18 in the sides of the chairs 6, thence upwardly through the horizontal portion 13 of the rail fasteners 100 12 and suitable nuts 19 are threaded upon the upper ends thereof whereby to securely retain the rail fasteners in their effective positions.

In Fig. 4, we have illustrated a slightly 105 modified form of the invention, wherein the rail fastener, as shown, is constructed to adapt the same for connection to the meeting ends of two rails and in this form of fastener, the horizontal or body portion 13' 110

and the flange 14', are extended longitudinally so as to bear against the base flanges of the rails and also abut against the web portions thereof, whereby they may be secured in position by means of the transverse bolts 20. The downwardly extending portions 15' which are arranged in spaced relation, are adapted to bear against the upper faces of the bodies of the ties to retain the rails against lateral movement, as herein set forth. From this it will be apparent that the device not only retains the rails in position upon the ties, but at the same time, connects the meeting ends of two rails and securely retains them against any lateral movement whatever.

It will be noted that by having the openings 18 elongated in form, the rail chairs 12 may be readily adjusted laterally with respect to each other, according to the gage of the track desired.

It will also be apparent that we have provided a simple and durable rail fastener which is to be used in connection with our improved railway tie, but it will be understood that it may be used equally as well with various other forms of ties.

The device, as herein shown and described, is extremely simple in construction and can be manufactured and placed upon the market at a comparatively low cost.

While we have shown and described the preferred form of our invention, it will be obvious that various changes in the details of construction and in the proportions may be resorted to for successfully carrying our

invention into practice, without sacrificing any of the novel features or departing from the scope of the invention, as defined by the appended claim.

Having thus described this invention, what we claim is:

A device of the class described including a tie provided upon its upper face with transverse serrations, rail chairs mounted upon said tie and having serrations adapted for engagement with the serrations on the tie, said rail chairs having upwardly extending flanges formed upon the longitudinal edges thereof upon the upper face and downwardly projecting flanges at the ends thereof, fastening means including a horizontal body portion having a downwardly depending flange upon one edge thereof, serrations formed upon the lower edge of said flange to engage the serrations on the tie, an upwardly projecting flange formed on the body of the fastener and adapted to be arranged parallel with the webs of the rails, bolts extending through the upper flanges and through the webs of the rails, and bolts extending through the tie and through the body of the fastener, whereby to securely retain the rails in position.

In testimony whereof we hereunto affix our signatures in the presence of two witnesses.

WILLIAM S. MAGEE.
CHARLES R. McCARREN.
